UNITED STATES PATENT OFFICE.

JAMES J. SANTIN AND GEORGE M. WHITE, OF EL RENO, OKLAHOMA.

TRAFFIC-SIGNAL FOR MOTOR-VEHICLES.

1,398,653.

Specification of Letters Patent.

Patented Nov. 29, 1921.

Application filed January 17, 1921. Serial No. 437,977.

To all whom it may concern:

Be it known that we, JAMES J. SANTIN and GEORGE M. WHITE, citizens of the United States, residing at El Reno, in the 5 county of Canadian and State of Oklahoma, have invented certain new and useful Improvements in Traffic-Signals for Motor-Vehicles, of which the following is a specification.

This invention relates to an improved traffic signal for motor vehicles and has as one of its principal objects to provide a simple and efficient device of this character whereby a driver may readily indicate an 15 intended course of action.

The invention has as a further object to provide a device which may be readily mounted at the front of the vehicle and which may be easily operated for indicating 20 an intention to turn either to the right or left or to continue straight ahead.

And the invention has as a still further object to provide a device which may be mounted upon the engine hood of the vehicle 25 and wherein the hood may serve as a housing for the actuating mechanism of the device.

Other and incidental objects will appear hereinafter.

30 In the drawings:

Figure 1 is a fragmentary side elevation showing our improved device in connection with a motor vehicle of conventional design, parts being broken away and shown in section,

Fig. 2 is an enlarged fragmentary sectional view more particularly illustrating the mounting of the device upon the engine hood of the vehicle,

Fig. 3 is a fragmentary horizontal section on the line 3—3 of Fig. 2 particularly illustrating the actuating mechanism for the indicator employed,

Fig. 4 is a perspective view showing the 45 indicator in detail,

Fig. 5 is a detail section taken through the wrist portion of the indicator,

Fig. 6 is a side elevation showing a slight modification of the invention, a vehicle of 50 conventional design being illustrated in dotted lines, and

Fig. 7 is a detail section on the line 7—7 of Fig. 6.

In order that the construction, mounting 55 and operation of our improved device may be accurately understood, we have, in the

drawings, shown the invention in connection with a motor vehicle of the conventional design. The vehicle is indicated at 10 and the engine hood thereof at 11. As 60 is usual, this hood is formed of swingingly connected sections having mating hinge loops 12 through which is fitted a hinge rod 13 joining the sections. The instrument board of the vehicle is indicated at 14. In 65 carrying the invention into effect, we employ a substantially U-shaped supporting frame 15 the upper side portion of which is, as particularly shown in Fig. 2, bent to provide a loop 16. In installing the device, 70 one of the hinge loops 12 of the engine hood of the vehicle is removed in order that the loop 16 may be accommodated upon the hinge rod 13 of the hood and, as will be noted, the rod is arranged to extend through 75 said loop supporting the frame beneath the hood. The hood will thus serve to house and protect the frame as well as the mechanism carried thereby. Journaled through the free end portions of the sides of the 80 frame is a vertically disposed tubular stub shaft 17 upon the upper end portion of which is threaded a nut 18 coacting with the upper side of the frame for sustaining the shaft. The shaft projects freely through 85 a suitable opening in the hood 11 and rising from said shaft is a post 19 bent in such manner that the upper end portion of said post normally lies directly over the hinge rod of the engine hood. Formed in the 90 upper end of the stub shaft are, as shown in detail in Fig. 4, oppositely disposed notches 20 and fixed in a suitable slot in the lower end portion of the post is a transverse key 21 normally engaging in said notches 95 and detachably connecting the post to the shaft to turn therewith. Suitably fixed upon the upper end of the post is an indicator 22 preferably in the shape of a hand and, as particularly shown in Figs. 4 and 100 5, the wrist portion of said hand is formed to provide a lamp housing 23. In the sides of said housing are preferably red panes 24 while in the front wall of the housing at opposite sides of the hand are preferably 105 white panes 25. A suitable electric lamp 26' is mounted within the housing and wires lead upwardly through the stub shaft 17 and post 19 to the lamp, the lamp being connected with the battery or other 110 suitable source of electrical energy upon the vehicle. Thus, at night when the lamp is

energized, a red light will show at opposite sides of the indicator while a white light will be thrown upon the hand so that said hand will be readily visible.

5 Fixed to the stub shaft 17 between the sides of the frame 15 is an arm 26 connected with the shaft by a suitable set screw and 10 slideable upon the lower side portion of the frame beneath said arm is, as particularly shown in Fig. 3, a combined actuating and stop plate 27. The plate is substantially semi-circular and formed in said plate to freely receive the stub shaft 17 therethrough, is an elliptical slot 28. Formed in 15 the free end portion of the arm 20 is a longitudinally extending slot 29 and extending freely therethrough is headed post 30 fixed to the plate and connecting the plate with the arm. Extending from the rear portion 20 of the plate is a lug 31 and riveted or otherwise secured to said lug is an actuating rod 32 which extends rearwardly beneath the engine hood 11 through the vehicle dash and through a suitable opening 33 in the 25 instrument board 14 of the vehicle. Fixed to said board at the lower side of this opening is a catch plate 34 and formed in the rod to coact with said plate is a bow 35 holding the stub shaft against rotation so that the 30 indicator 22 will normally project forwardly. When in this position, the indicator will, of course, denote an intention of the driver to continue straight ahead.

As will now be readily understood in view 35 of the preceding description, by pulling rearwardly upon the rod 32, the stub shaft 17 may be rotated a quarter turn to the right. The indicator will then be moved to point toward the right for indicating an intention 40 of the driver to turn accordingly. On the other hand, by pushing forwardly upon the rod, the stub shaft may be rotated a quarter turn to the left. The indicator will then be disposed to point toward the left for indicating 45 an intention of the driver to turn in this direction. Thus, the indicator may be readily manipulated. In this connection, it will be noted that when the rod 32 is moved longitudinally, the plate 27 will slide 50 upon the lower side of the frame 15 being guided by the stub shaft 17 riding within the slot 28 while the post 30 will slide within the slot 29 of the arm 26 for swinging the arm as the plate is shifted. When the stub 55 shaft reaches one end of the slot, as for instance, when the plate is pulled rearwardly, said shaft will coact with the plate for limiting the plate and accordingly limiting the shaft in its rotative movement so 60 that the indicator cannot be shifted more than a quarter turn to the right and similarly, when the post reaches the opposite end of the slot, the plate will coact with the post for limiting the indicator in its rotative 65 movement to the left.

In Figs. 6 and 7 of the drawings, we have illustrated a slight modification of the invention wherein a pair of signals is employed, one near the front of the vehicle and the other at the rear thereof. For convenience, a vehicle of conventional design has been illustrated at 36. Mounted upon the engine hood of the vehicle is an indicator 37 and associated mechanism as disclosed in the preferred form of the invention, an actuating rod 38 extending rearwardly through the vehicle dash. In this modification, a bracket 39 is employed, this bracket being appropriately secured at any suitable point at the rear of the vehicle. As 70 will be observed, the bracket is formed with spaced side portions and between said side portions is an actuating plate and associated mechanism similar to the plate 27 and associated mechanism of the preferred construction. Operable by said plate is an upstanding post 40 to the upper end of which is secured an indicator 41 corresponding to the indicator 22 and extending forwardly from the plate is an actuating rod 42. 75 Clamped around the steering post is a bracket 43 having a depending arm 44 and pivoted upon said arm is a control lever 45. Upstanding from this lever is a post 46 to which the rod 38 is connected and extending downwardly from the lever is a rod 47. Mounted at a suitable point beneath the vehicle is a bracket 48 upon which is pivoted a bell crank 49 and, as will be noted, the rod 47 is connected to one arm of this lever while 80 the rod 42 is connected to the other arm thereof. Thus, when the lever 45 is rocked both of the indicators 37 and 41 will be moved accordingly. As shown in detail in Fig. 7, the lever 45 is connected to the arm 44 by a pivot bolt 50 and surrounding said bolt in a spring 51 tensioning the lever against the arm. The lever is formed near its inner end with a transverse groove while the arm is provided with a rib engaging in 85 said groove so that normally, the lever will be yieldably locked in a horizontal position when both indicators will point forwardly. As will be seen, this modified structure provides an arrangement whereby a signal may 90 be displayed both at the front and rear of the vehicle coincidently.

Having thus described the invention, what is claimed as new is:

1. A traffic signal including a rotatable 120 shaft, an indicator connected therewith, an arm extending from the shaft, and slideable means connected with said arm movable for swinging the arm and rotating the shaft, said means being formed to coact with the 125 shaft whereby said means will be limited in its movement.
2. A traffic signal including a rotatable 130 shaft, an indicator connected therewith, an arm extending from the shaft, and means

- mounted to ride upon the shaft transversely thereof and being slidably connected with the arm movable for swinging the arm and rotating the shaft, said means being formed 5 to coact with the shaft whereby said means will be limited in its movement.
3. A traffic signal including a rotatable shaft, an indicator connected therewith, an arm extending from the shaft, and a reciprocal actuating plate mounted to ride upon the shaft transversely thereof and being connected with said arm movable for swinging the arm and rotating the shaft, said plate being formed to coact with the 10 shaft whereby said plate will be limited in its movement.
4. A traffic signal including a rotatable shaft, an indicator connected therewith, an arm extending from the shaft and means 15 connected with said arm and having a slot receiving the shaft therethrough to ride upon the shaft transversely thereof, said means being movable for swinging the arm and rotating the shaft and the shaft being adapted to engage the end walls of said slot 20 selectively for limiting said means in its movement in opposite directions.
5. A traffic signal including a rotatable shaft, an indicator connected therewith, an arm extending from the shaft, and an actuating plate connected with said arm and having a slot receiving the shaft therethrough to ride upon the shaft transversely thereof, said plate being movable for swinging the arm and rotating the shaft and the shaft being adapted to engage the end walls 25 of said slot selectively for limiting said plate in its movement in opposite directions.
6. A traffic signal including a rotatable shaft, an indicator connected therewith, an arm extending from the shaft and provided 30 with a slot, and actuating means for the shaft having a post extending freely through said slot connecting said means with the arm, said means being mounted to ride 35 upon the shaft transversely thereof and being movable for swinging the arm and rotating the shaft.
7. A traffic signal including a frame, a shaft journaled thereon, an indicator connected with the shaft, an arm fixed to the shaft, an actuating plate having a slot freely receiving the shaft therethrough, the arm being provided with a slot, and a post fixed to the plate and extending freely through 40 the latter slot, the plate being shiftable for swinging the arm and rotating the shaft and the shaft being adapted to engage the end walls of said first mentioned slot selectively for limiting the plate in its movement in opposite directions.
8. The combination with a motor vehicle provided with an engine hood having a hinge rod, of a frame secured beneath the hood and looped over said rod, a shaft journaled upon the frame, an indicator connected with said shaft through the hood, and means for rotating the shaft.
9. A traffic signal including a rotatable shaft, a plate having a curved slot freely 45 receiving the shaft therethrough whereby the plate may be shifted upon the shaft transversely thereof, an arm extending from the shaft, and an operative connection between the arm and plate, the plate being 50 movable for swinging said arm and rotating the shaft.
- In testimony whereof we affix our signatures.
